CLAIM

The ornamental design for a roasting tray, as shown and described.

DESCRIPTION

FIG. 1 is a front, top perspective view of a roasting tray, showing my new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of a portion indicated in FIG. 1. The broken lines in the figures illustrate portions of the roasting tray that form no part of the claimed design. The dash dot dash lines in FIGS. 1 and 8 are for the purpose of depicting the cut line of the enlarged view and form no part of the claim.

1 Claim, 8 Drawing Sheets
